UNITED STATES PATENT OFFICE.

ALBURT N. SIMMERLY, OF CLEVELAND, OHIO.

COAL OR ORE BUCKET OR CARRIER.

SPECIFICATION forming part of Letters Patent No. 311,789, dated February 3, 1885.

Application filed December 12, 1884. (No model.)

To all whom it may concern:

Be it known that I, ALBURT N. SIMMERLY, a citizen of the United States, residing at Cleveland, in the county of Cuyahoga and State of Ohio, have invented certain new and useful Improvements in Coal or Ore Buckets; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to buckets or carriers for coal, ore, or the like; and the novelty consists in the construction, arrangement, and adaptation of parts, as will be more fully hereinafter set forth, and specifically pointed out in the claims.

For convenience, I will illustrate the invention as applied to a dumping-bucket, adapted to be raised by any ordinary power upon a swinging crane; but the features of importance will be understood to serve with equal success in other relations.

My bucket is preferably made of sheet metal, and has a bottom inclining in opposite directions from a central line. The bucket has hinged doors upon opposite sides, the hinges being uppermost, and from each door curved links extend inward past each other, and are secured to cross-bars upon a rock-shaft in such a manner that the points of connection, when the doors are closed, are in a position past the center of motion of the rock-shaft. This position firmly locks the doors in place and avoids the necessity of any securing devices whatever, while the greater the pressure upon the doors the more firmly will they be locked, until a lever is operated to force the pivots upon the other side of the center, when the pressure upon the doors will open them. I propose that this lever shall be operated from a distance, as by the engineer, and thus avoid the necessity of employing a man as a dumper.

A considerable percentage of loss is sustained in handling coal or ore, due to the breaking up of the material. This loss, where turning-buckets are used, has been estimated at eighteen per cent. This is due to the fact that the necessary room for turning the bucket gives

more or less fall to the contents—say six or seven feet.

In my construction the bucket may be lowered as far as desired, and by the proper manipulation of the lever the contents may be easily deposited where required without any appreciable shock or damage.

The invention is illustrated in the accompanying drawings, which form a part of this specification, and in which—

Figure 1 is a vertical cross-section; Fig. 2, an elevation of one end, showing the operating-lever; Fig. 3, an elevation of the opposite end; 65 Fig. 4, a side elevation, broken away to show internal parts.

Referring to the drawings, in which similar letters of reference indicate like parts in all the figures, A designates the body of the bucket, having a bottom, B, inclining in opposite directions from a central line, b, as shown. These parts are preferably made of proper metal, and the bucket is preferably rectangular. Upon each side is formed, from a point near the vertical center downward, an exit-aperture, C, controlled by a door, D, hinged above, as shown at d, and so arranged as to completely close the aperture C by its gravity. Passing through the ends, and under and along the line b, is a rock-shaft, E, and rigid with this rock-shaft, and arranged upon the ends thereof which project outside the ends of the bucket, are two cross-arms, F, and to these arms are loosely pivoted curved links f and f'. Each link f is pivoted at one end to lug d' upon one door, and extends past the rock-shaft E, and has its opposite end loosely pivoted to the end of the cross-arm, while the link f' serves similarly between the opposite door and the other end of the cross-arms.

By reason of the curvatures seen at f² in each of the links the pivotal points marked x x' are carried beyond the center of motion of the rock-shaft before the links come into contact therewith, and in this feature lies an important function. The parts mentioned—that is to say, the doors, rock-shaft, cross-arms, and links—are so proportioned to each other that when the doors are squarely closed the concave sides of the links lie in contact with the rock-shaft, or nearly so, and the pivots x x' lie slightly beyond the axis of motion of the rock-shaft above or below. Hence any press-

ure upon the doors from the inside serves to lock them more securely.

I provide upon one end of the bucket a lever, G, which lies in a plane parallel with that of the cross-arms F, and it is made rigid with the rock-shaft. A rope, as H, may be secured to said lever and passed over a pulley, h, or through the eye of the bail I, or elsewhere, and, running back to the engineer, may be employed to unlock the doors. This unlocking is very easily accomplished. A slight force will serve to oscillate the rock-shaft until the pivots $x x'$ pass the center, when the pressure upon the doors will complete the operation. After the contents have been deposited the doors, by their gravity, close, and the weight of the lever throws the points $x x'$ past the center, ready for another charge.

This application is made with full knowledge of a dumping-car shown in Patent No. 26,460, of 1859. I desire to fully recognize the state of the art as evidenced in said patent. The bottom, the receptacle, and doors in that patent served a similar purpose; but the connecting-links never went past the center of motion of the rock-shaft, and there was always a danger of the fastening jarring loose. This danger was so apparent that an independent catch to lock the lever was employed.

In my device I utilize the gravity of contents being carried to lock the doors.

What I claim as new is—

1. In a coal-carrier, substantially as described, in combination with the bucket or receptacle A, having double-inclined bottom B, doors D, and rock-shaft, as E, curved links connecting each door to pivots beyond the shaft and past the axis of its motion, whereby the weight of the contents will increase the security of the lock, and a lever, as G, adapted to oscillate the rock-shaft to release the lock, as set forth.

2. The coal-bucket described, consisting of the body A, having exit-apertures C, double-inclined bottom B, doors D, and rock-shaft E, having cross-arms F, the links $f f'$, curved, as seen at f^2 , and connecting the lugs d upon the doors with the pivots $x x'$ upon the cross-arms, the lever G, rigid with the rock-shaft, and the rope H, adapted to manipulate the locking devices from a distance, as and for the purposes set forth.

In testimony whereof I affix my signature in presence of two witnesses.

ALBERT N. SIMMERLY.
